DESIGN FOR A COMBINED WASHING MACHINE AND WRINGER

Fred A. Conterman, Jamestown, N. Y., assignor
to Blackstone Manufacturing Company, Inc.,
Jamestown, N. Y., a corporation of New York

Application June 11, 1936, Serial No. 63,234

Term of patent 14 years

To all whom it may concern:

Be it known that I, Fred A. Conterman, a citizen
of the United States, residing at Jamestown, in
the county of Chautauqua and State of New York,
have invented and produced a new, original, and
ornamental Design for a Combined Washing Ma-
chine and Wringer, of which the following is a
specification, reference being had to the ac-
companying drawing forming part thereof, and
in which

Figure 1 is a front perspective view of a com-
bined washing machine and wringer, showing my
new design;

Figure 2 is a side perspective view; and
Figure 3 is a plan view.

I claim:

The ornamental design for a combined washing
machine and wringer, as shown.

FRED A. CONTERMAN.
